United States Patent Office

Des. 195,506
Patented June 25, 1963

195,506

WHEEL

Romayne E. Holmes, Jr., Madison Heights, Mich., assignor to Kelsey-Hayes Company, Romulus, Mich., a corporation of Delaware

Filed July 9, 1962, Ser. No. 70,832

Term of patent 14 years

(Cl. D14—30)

FIG. 1 is a perspective of a wheel showing my new design; and

FIG. 2 is a diametrical cross-section through the wheel. The dominant features of my design reside in the portions shown in full lines.

I claim:

The ornamental design for a wheel, substantially as shown and described.
